UNITED STATES PATENT OFFICE

EMIL A. HIRNER, OF ALLENSTOWN, PENNSYLVANIA

WRINGER

Application filed July 24, 1928. Serial No. 295,032.

This invention relates to wringers of the power driven reversible kind ordinarily associated with domestic washing machines. More specifically speaking, this invention is concerned with feed means for wringers of the type mentioned, and may be regarded as an improvement over the structure disclosed in my prior U. S. Patent No. 1,683,352, dated September 4, 1928; and filed by me on December 15, 1927, under Serial No. 240,089. In the aforesaid patented structure, a feeding element having the form of a tongue bar is movable from a normal retracted or loading position toward the squeeze rollers of the wringer in presenting the leading margin of the material to be wrung, after having been laid over said bar, before the entrant bight between the squeeze rollers. Incidental to feeding, a cooperating member acts to check rearward movement of the material on the bar to insure its being nipped by the squeeze rollers.

Amongst the objects of my present invention are to provide not only for positional adjustment of the feed bar vertically relative to the level of the squeeze rollers, but to enable lateral adjustment thereof into true alignment and parallelism with said rollers; to provide against splash or spill of the water wrung out beyond the ends of the feed bar; to insure positive engagement of the material on the bar by the cooperating check member; and to enable said check member to be moved and held out of the way when it is not needed.

In addition to the foregoing, I aim to secure the advantages accruing to simplified construction and arrangement of the parts involved in feeding the material to the squeeze rollers of the wringer.

Still other objects and attendant advantages will be apparent from the detailed description which follows when taken in connection with the attached drawings, wherein in Fig. I is a front elevation of a power wringer conveniently embodying my invention.

Fig. II is a fragmentary end elevation of the wringer viewed from the right of Fig. I.

Fig. III is a plan section, taken as indicated by the arrows III—III in Figs. I and II, with the upper squeeze roller removed.

Fig. IV is a fragmentary vertical section of the wringer, taken as indicated by the arrows IV—IV in Figs. I and III.

Fig. V is a perspective view of the feed bar that is functional in presenting the material, which is to be wrung, to the squeeze rollers of the wringer.

Fig. VI is a similar view of the member for checking rearward movement of the material on the feed bar aforesaid, incidental to advancement between the feed rollers; and,

Fig. VII is an exploded view showing, in perspective, the various relatively adjustable parts which together constitute one of the end mountings for the feed bar.

The wringer herein illustrated is, generally speaking, standard in construction, i. e., it embodies a yoke-like frame 10 with suitable bearings in its vertical end portions, to rotatably support the rubber covered squeeze rollers 11, 12, and enclosing gearing to drive said rollers. At opposite sides beneath the squeeze rollers 11, 12, the wringer is equipped with counter-sloping drain chutes 13, 14 and between these is mounted an auxiliary drain chute 15 which is centrally pivoted at 16, so as to be tiltable for cooperation with either of the fixed chutes 13, 14 as required for either forward or reverse operation of the wringer. A bracket partly shown at 17, in Figs. I and III, serves to support the wringer after the manner of a cantilever horizontally over the receptacle of the washing machine, said bracket being hollow for the passage of the driving connections (not shown) to the squeeze rollers 11, 12. In standard wringers of the kind briefly described, mechanism is provided to enable reverse operation of the squeeze rollers 11, 12, but since such mechanism is not pertinent in the present connection, a showing thereof has also been omitted from the drawings.

The feeding means herein featured comprises a bar 18 with a tongue-like forward edge 18a, said bar being swingable upward from the substantially horizontal loading position, indicated in dot-and-dash lines in Fig. I.

II, to the upright active position, indicated in full lines in Figs. II and III, in presenting the material M which is to be wrung to the squeeze rollers 11, 12. As shown, the bar 18 affords a longitudinal hollow for accommodation of an auxiliary feed roll 19, and at opposite ends has side arms 20, with integrally formed pivot trunnions 21, as well as with laterally projecting manipulating handles 22. Hollowed out transverse guard portions 23 at the ends of the feed bar 18, immediately inward of the side arms 20, serve to control flow of the liberated or wrung-out water incidental to passage of the material M between the squeeze rollers 11, 12 in a manner more fully explained later. From Figs. II and IV, it will be observed that the pivot trunnions 21, are engaged within open top notches 24 of a pair of bearing pieces 25, which have pivotal support on screw studs 26, Fig. VII, respectively let into brackets 27, the latter being secured to the frame 10 of the wringer at one side. Dislodgement of the trunnions 21, is prevented by gravity keepers 28, which are supported for free swinging movement on studs 29, taking into the bearing pieces 25. As a consequence of such pivoting, the bearing pieces 25 can be adjusted laterally relative to the brackets 27, for the purpose of securing true alignment and parallelism of the feed bar 18 relative to the squeeze rollers 11, 12 horizontally, the adjustment being fixable by means of clamp screws 30, that pass through arcuate slots 31 in said bearing pieces 25 and engage in lugs 32 of the brackets 27. Upward movement of the feed bar 18 is limited by stops in the form of screw studs 33, adjustable in the brackets 27. Set screws 34 prevent loosening of the stops 33 after the desired adjustment is secured. As shown in Fig. VII the brackets 27 have vertical slots 35, 36 at the top and bottom for passage of securing screws 37, 38, the described arrangement permitting up and down adjustment of the feed bar 18 for proper leveling in relation to the squeeze rollers 11, 12. In order to enable transposal of the feed bar 18, a pair of brackets 27a is provided at the opposite side of the wringer frame, the said brackets being identical, both as regards construction and appendages, to the brackets 27 previously described: and, in order to avoid confusion, all corresponding parts shown at the right-hand of Figs. II, IV, as well as the upper half of Fig. III, are distinguished by a primed "a". To remove the feed bar 18 for the purpose mentioned, the gravity keepers 28 are simply swung inwards to clear the trunnions 21 whereupon the latter may be readily withdrawn from the open top bearings 24. On the other hand, in attaching the feed bar 18, the keepers 28 will obviously yield to deflection incidental to placement of the trunnions 21 into the notched bearings 24. To prevent rearward slippage of the ma-

terial M on the bar 18 incidental to feeding, I provide the check member designated by the numeral 39. This check member 39 is hung in free suspension from a supporting element 40 having the form of a yoke with side arms 41, pivoted at 42, to the brackets 27. As shown in Figs. I and III the rounded central portion of the supporting element 40 is engaged by suspension ears 45 of the check member 39. These ears 45 are preferably fashioned from stout wire (see Fig. VI) the ends of the wire being bent laterally as at 46 for force fitment into receiving openings 47 in the thickened end portions 48 of the check member 39. Endwise movement of the member 39 is prevented through engagement within a notch 49 extending circumferentially about its rounded upper edge portion, of a central collar 50 on the supporting element 40. The described construction facilitates ready assembling of the parts, the procedure being as follows: the check member 39 is brought up so that its notch 49 registers with the collar 50 of the supporting element 40 and the wire ears 45, after having previously been placed on said supporting element, forced into the apertures 47. As shown in Figs. I, III and VI, the free edge of the check member 39 is serrated as at 51 to more effectively engage the material M on the feed bar 18. When active, the check member 39 rests in an inclined position on the feed bar 18 as shown in Figs. II and IV, the supporting element 40 being at this time sustained horizontally through engagement of its side arms 41 with shoulders 52 on the brackets 27. For the purpose of holding it in raised position out of the way, when it is not needed, the check member 39 is provided with an aperture 53 engageable with a projection 54 on the wringer frame 10. For convenience, the wringer is equipped with a duplicate check member 39a at the opposite side (Figs. II and IV) for cooperation with the feed bar 18 when the latter is transferred to that side of the wringer, said check member 39a being shown in the raised inactive position. In the use of my invention, a margin of the material M to be wrung is laid over the feed bar 18 when the latter is in the lowered or dot-and-dash line position of Fig. II. The feed bar 18 is then grasped by the manipulating handles 22 and raised to the full line position of Figs. II, III and IV, the check member 39 being incidentally encountered and thereby caused to assume the angular position shown in Figs. II and IV. Immediately upon grippage of the lapping portion of the material M between the auxiliary feed roll 19 and the lower squeeze roll 12, it is automatically fed forward and rolled into the entrant bight between the two co-operating squeeze rollers 11, 12, this being made possible through the holding action of the check member 39. As the material passes

through the squeeze rollers 11, 12, the released or squeezed out water is prevented from splashing or dripping over the ends of the feed bar 18, down along the brackets 27 and beyond the confines of the drain chutes 13, 14, as a consequence of interception and downward deflection within the hollows of the guard portions 23 on said bar.

From the foregoing it will be seen that I have provided a simple and inexpensive safety feed device which possesses all the attributes of my previous invention disclosed in the patent supra, as well as the herein-described refinements, to wit: the provisions enabling accurate alignment and leveling of the feed bar 18 with respect to the squeeze rollers 11, 12 for maintenance of the proper cooperative action between these parts with assurance of positive feeding; the provisions for diverting the released or squeezed out water so that it is directed back into the tub of the washing machine; and the provisions promoting action of the material checking member 39 as well as facilitating assembling of its parts.

Having thus described my invention, I claim:

1. In a wringer, a pair of cooperating squeeze rollers, feeding means in the form of a tongue bar having side arms with pivot trunnions and adapted to be overlapped by a margin of the material which is to be wrung for presentation of such material to the bight of the squeeze rollers, pivotally suspended bearing members engaged by the pivot trunnions aforesaid to support the bar for swinging movement toward and away from the squeeze rollers, and means enabling individual vertical as well as lateral adjustment of the bearing members to properly position the bar at the level of the squeeze rollers in true alignment and parallelism respectively with the latter.

2. In a wringer, a pair of cooperating squeeze rollers, feed means in the form of a tongue bar adapted to be overlapped by a margin of the material which is to be wrung for presentation of such material to the bight of the squeeze rollers, and pivotally-suspended individually-adjustable bearing members having gravity keepers to support the tongue bar at opposite ends for horizontal movement into true alignment and parallelism with the squeeze rollers, and with capacity for easy removal, respectively.

3. In a wringer, a pair of cooperating squeeze rollers, feeding means in the form of a tongue bar having side arms with pivot trunnions and adapted to be overlapped by a margin of the material which is to be wrung for presentation of such material to the bight of the squeeze rollers, vertically adjustable brackets at opposite ends of the wringer frame, and members with open top notches pivotally associated with the brackets to sup-

port the feed bar by the trunnions aforesaid for movement toward and away from the squeeze rollers, said members being separately adjustable relative to the brackets to enable horizontal aligning of the bar with respect to the body of said squeeze rollers.

4. In a wringer, a pair of cooperating squeeze rollers, feeding means in the form of a tongue bar adapted to be overlapped by a margin of the material which is to be wrung for presentation of such material to the bight of the squeeze rollers, pivotally suspended members having open top notches to support the feed bar with capacity for swinging movement toward and away from the squeeze rollers, and means enabling adjustment of the vertical level of the bar in respect to the squeeze rollers as well as alignment thereof horizontally with the body of said rollers.

5. In a wringer, a pair of cooperating squeeze rollers, feeding means in the form of a tongue bar having side arms with pivot trunnions and adapted to be overlapped by a margin of the material which is to be wrung for presentation of such material to the bight of the squeeze rollers, means supporting the bar with capacity for swinging movement toward and away from the squeeze rollers including brackets separately adjustable vertically at opposite sides of the wringer frame to enable leveling of the bar in respect to the feed rollers, bearing elements having open top notches engaged by the trunnions, said elements being in turn pivoted to the brackets aforesaid with capacity for individual adjustment to enable true horizontal aligning of the bar relative to the bight of the squeeze rollers.

6. In a wringer, a pair of cooperating squeeze rollers, an underlying drain to catch the water wrung-out, feeding means in the form of a tongue bar adapted to be overlapped by a margin of the material which is to be wrung for presentation of such material to the bight of the squeeze rollers, and means to prevent flow of the water wrung-out over the ends of the tongue bar beyond the confines of the underlying drain.

7. In a wringer, a pair of cooperating squeeze rollers, an underlying drain to catch the water wrung-out, and feeding means in the form of a tongue bar adapted to be overlapped by a margin of the material which is to be wrung for presentation of such material to the bight of the squeeze rollers, said feed bar being formed with water diverting hollows transverse to the tongue bar which prevent flow of the released water over its ends and beyond the confines of the underlying drain.

8. In a wringer, a pair of cooperating squeeze rollers, feeding means in the form of a tongue bar embodying a longitudinal hollow affording accommodation for an auxiliary feed roller and flanking transverse hol-

- lows, said bar being adapted to be overlapped by a margin of the material which is to be wrung for presentation of such material to the bight of the squeeze rollers, and co-operative means to check rearward slippage of the material on the bar incidental to feeding including a member hung in suspension above said bar and provided with a lower serrated edge to engage the material.
- 20 9. In a wringer, a pair of cooperating squeeze rollers, feeding means in the form of a tongue bar adapted to be overlapped by a margin of the material which is to be wrung for presentation of such material to the bight of the squeeze rollers, means to check rearward slippage of the material on the bar incidental to feeding including a member hung in suspension above said bar, and means for holding the check bar in upwardly swung position out of the way when it is not needed.
10. In a wringer, a pair of cooperating squeeze rollers, feeding means in the form of a tongue bar adapted to be overlapped by a margin of the material which is to be wrung for presentation of such material to the bight of the squeeze rollers, means to check rearward slippage of the material on the bar incidental to feeding including a check member hung in suspension above said bar, and an element to so support the check member, said element having a rounded portion engaged by suspension ears formed of single lengths of wire with lateral projections engaged in apertures in the ends of said check member with a force fit.

In testimony whereof, I have hereunto signed my name at Allentown, Pa., this 19th day of July 1928.

EMIL A. HIRNER.
